CLAIM

The ornamental design for a combined mailing envelope and sampler therefor, as shown and described.

DESCRIPTION

FIG. 1 is a rear perspective view of a combined mailing envelope and sampler therefor, showing my new design in a partially opened position;

FIG. 2 is a front perspective view thereof;

FIG. 3 is an enlarged sectional view thereof, taken along line 3—3 of FIG. 1.

FIG. 1

FIG. 2

FIG. 3
